COIL WINDING MACHINE

Edward W. Collins, Anderson, Ind., assignor to
General Motors Corporation, Detroit, Mich., a
corporation of Delaware

Application December 9, 1935, Serial No. 53,489

17 Claims. (Cl. 140—92.2)

This invention relates to winding machines and more particularly to an improvement in a coil winding machine such as disclosed in my prior Patent No. 1,995,916, issued March 26, 1935.

5 In my prior machine, manipulation of a foot pedal results in (a) separation of complementary winding forms for removal of a wound coil therefrom, (b) release of the anchored coil lead from the winding form and of the coil end from the supply wire, and anchorage of the supply wire on the winding form for a new coil winding operation, and (c) a restart of the machine. The operator of the machine is instructed to manipulate the foot pedal during rest periods 10 of the machine only. However, there being no provision to guard against accidental manipulation of the foot pedal during a winding operation serious damage to the machine or at least a troublesome interruption of a winding operation 15 may result therefrom.

20 Therefore, it is one of the objects of the present invention to guard against accidental manipulation of the foot pedal during operation of the machine.

25 It is another object of the present invention to construct the foot pedal operated structure more simple and more rugged than in my prior machine.

Further objects and advantages of the present 30 invention will be apparent from the following description, reference being had to the accompanying drawings wherein a preferred embodiment of the present invention is clearly shown.

In the drawings:

35 Fig. 1 is a perspective view of a machine embodying the present invention.

Figs. 2 and 2a together represent a plan view of the machine.

40 Figs. 3 and 3a together represent a front elevation of the machine as viewed in the direction of arrow 3 in Fig. 1.

Fig. 4 is a perspective view of certain structure of the machine and is viewed in the direction of arrow 4 in Fig. 3a.

45 Fig. 5 is an enlarged fragmentary view of that part of the winding form which is surrounded by the dot-and-dash lines 20 in Fig. 2a.

Figs. 6 and 7 are perspective views of the cutting and bending blades of the machine.

50 Fig. 8 is a fragmentary front elevation of these same blades.

Fig. 9 is a fragmentary section taken on the line 9—9 of Fig. 5.

55 Fig. 10 is a fragmentary section taken on the line 10—10 of Fig. 2a.

Fig. 11 is a fragmentary section taken on the line 11—11 of Fig. 3a.

Fig. 12 is a section taken on the line 12—12 of Fig. 2a.

Fig. 13 is a fragmentary section taken on the line 13—13 of Fig. 12.

Fig. 14 is a fragmentary section similar to Fig. 12, showing, however, certain machine elements in a different position of operation.

Fig. 15 is a fragmentary section taken on the line 15—15 of Fig. 12.

The instant machine may for sake of better understanding be divided into several sub-structures, to wit:

A rotatable and separable winding form A, 15 a wire shifting device B, a wire anchoring and coil releasing device C and a machine stopping and restarting device D. These devices shall now be described in the just mentioned order.

Rotatable and separable winding form A 20

Referring to the drawings, the reference numeral 30 designates a base providing a number of spaced uprights 32, some of which provide bearings 34 for a power driven shaft 36 which 25 carries at one end a winding member 38 and intermediate its two bearings 34 a longitudinally immovable friction disc 40 (see Fig. 3). Suitably splined to shaft 36 is another friction disc 42, and journalled on the same shaft intermediate 30 both friction discs 40, 42 is a pulley 44 which is driven from any suitable power source (not shown) by means of a belt 46. Interposed between one of the bearings 34 and friction disc 42 is a compressed spring 48 which normally 35 urges disc 42 into driving frictional engagement with pulley 44 and the latter into frictional driving engagement with disc 40. Journalled and slidable in a bearing 50 on top one of the uprights 32 is a stub shaft 52 which is in axial alignment with shaft 36 and carries a winding member 54, adapted to cooperate with its companion member 38 to complete the winding form A which provides a winding groove 56. This winding groove may be of any desired shape or form 45 to accommodate any article to be wound therein. Stub shaft 52 with its winding member 54 may be withdrawn from its relatively stationary companion member 38 to permit the removal of a wound coil from the winding groove 56. To this 50 end joints 58 connect the stub shaft 52 with links 60 and 62 at 64. Link 62 is pivotally mounted at 66 on one of the uprights 32. Link 60 is pivotally connected at 68 to a bar 10 which is in turn connected with a foot pedal 12 by means 55

of a link 74. Foot pedal 72 is pivotally mounted at 76 on a bracket 78, suitably mounted on one of the posts 80 of the work bench or support 82 which carries the winding machine. A tension spring 84 normally urges link 60 into the position shown in Fig. 3a in which the links 58, 62 are in longitudinal alignment and member 54 is in cooperative engagement with its companion member 38. The winding members 38, 54 are 10 drivingly connected with each other when they are in cooperative engagement. Such driving connection may be established by the provision of suitable driving lugs (not shown) on both winding members which drivingly engage each other when said winding members are in cooperative engagement with each other. The joints or links 58 are pivotally connected at 86 to a collar 88 which is journaled on stub shaft 52 and prevented from sliding therefrom by a 20 shoulder 92. Stub shaft 52 with the winding part 54 may therefore rotate relative to the collar 88 whenever the machine is in operation. Stub shaft 52 also carries a suitable number of washers 94 against which rests a thrust bearing 96, 25 engaged by the collar 88. In this way the tension spring 84 has not only a tendency to return winding member 54 into cooperative engagement with its companion member 38 but also yieldingly to retain the former in cooperative engagement 30 with the latter as can be readily understood. It may be stated in advance that manipulation of the pedal 72 into the dot-and-dash position in Fig. 3a causes movement of bar 60 in the direction of arrow 98 and consequently results in a 35 retraction of winding member 54 from its relatively stationary companion member 38 so as to permit the removal of a wound coil 100 from the winding groove 56.

Wire shifting device B

Referring more particularly to Figs. 2, 2a, 3a, 10 and 11, a shaft 102 is journaled in suitable bearings 104 on the machine base 30. This shaft is spaced from, and parallel to, shaft 36 and carries near one end two identical ratchet discs 106 which are engaged by pawls 108, mounted on eccentrics 110 and 112 on shaft 36. A stud 114, carried by suitable lugs 116 of a bearing 34, holds leaf springs 118 in yielding engagement 50 with the pawls 108, thereby normally retaining the latter in engagement with their respective ratchet discs 106. The eccentrics 110 which have the same throw, are displaced 180° relative to each other so that during rotation of shaft 36 one 55 of the pawls indexes shaft 102 while the other pawl rides idly over its respective ratchet disc into position for the next indexing operation, and vice versa. It can now be understood that rotation of shaft 36 results in continuous but 60 considerably slower rotation of shaft 102. Pivotally mounted at 120 to a lug 122 of the machine base 30 is a wire shifter 124 which has two arms 126 and 128, carrying a grooved roller 130 and an antifriction roller 132, respectively. 65 Cooperating with the antifriction roller 132 is a cam disc 134 which is carried by the shaft 102 and adapted to cause oscillation of the wire shifter about its pivotal support so as properly to guide wire or other winding material 136 from 70 a suitable supply (not shown) into the winding groove 56. The winding material which runs in the groove of roller 130 is prevented from jumping said groove by means of a retainer blade 138 which is carried by the wire shifter in close proximity to the periphery of the roller as best shown 75

in Fig. 10. Roller 132 is normally held in engagement with cam disc 134 by means of a tension spring 140 which tends to rock a bell-crank lever 142, pivoted at 144 to bracket 78, clockwise as viewed in Fig. 3a thereby forcing 5 a floatingly pivotally connected rod 146 in the direction of arrow 148 and against arm 128 of the wire shifter.

Wire anchoring and coil releasing device C

As best shown in Figs. 2a, 3a and 5 the winding member 38 is provided with an oblique groove 150 which merges from, and returns to, the winding groove 56. This oblique groove 150 is traversed by a slot 152, two opposite walls of which 15 are lined with hardened steel plates 154. Wire severing and anchoring blades 156 are joined by means of a pin 158 and are pivoted at 160 in slot 152 of the winding member 38 (see Fig. 3a). Slot 152 is parallel to the axis of rotation of the winding head A and is considerably deeper and wider than groove 150. Groove 150 which is shallow and rather narrow, receives the wire 136 to be traversed and anchored by the blades 156. Blade 156a is provided with a shearing 25 edge 162 which is adapted to cooperate with a shearing edge 164 of one of the hardened plates 154, and the other blade 156b has two edges 166 and 168, one above the other and separated by a tooth 170. Edge 166 is dull and is only a 30 bending edge, while the other edge 168 is a shearing edge.

For an initial coil winding operation, the leading end of the wire as it comes from the wire guide is disposed in the groove 150. The blades 35 156 at this time are in the dot-and-dash position of Fig. 9 in which the tooth 170 partly traverses the slot so that the wire rests on said tooth. Upon movement of the blades 156 from the dot-and-dash position toward the full line position 40 shown in Fig. 9 by means to be described later, the shearing edges 162 and 164 of blades 156a and plate 154, respectively, cooperate to sever excessive length from the leading end of the wire, leaving sufficient wire length in the slot 45 152 for the formation of an anchor. This anchor is formed upon continued movement of the blades 156 into the full line position shown in Fig. 5, whereby the dull edge 166 of blade 156b forces the wire end into engagement with 50 the plate 154, i. e. into the dot-and-dash position in Fig. 5. In this manner the leading end of the supply wire is anchored to the winding head A, and upon rotation of the winding head in counterclockwise direction as viewed in 55 Fig. 1, the anchored, leading end of the supply wire is immediately guided into the winding groove 56 of the winding head by the shallow groove 150 as can be readily understood. Continued rotation of the winding head A causes 60 the deposition of continuous layers of wire in the winding groove 56 under the control of the previously mentioned wire shifter B. For the actual winding of a coil, the wire shifter is oscillated by the cam 134 only to such an extent as 65 to laterally shift the wire throughout the width of the winding groove 56a. During the winding of the last layer of a coil, a single cam lobe 174 rocks the wire shifter into the dot-and-dash position in Fig. 10 in which the wire is shifted 70 out of the winding groove 56 of the winding head and into the shallow groove 150, whereby the machine comes to rest just when the winding head assumes the position shown in Figs. 1, 2a, 3a, and 11, in which the blades 156 are in 75

alignment with a plunger 176, adapted to actuate these blades. In order to understand the following description of the severance of the wound coil from the supply wire and the anchorage of the latter to the winding head, it is to be understood that the blades 156 are immediately returned into the dot-and-dash position in Fig. 9 at the start of the just completed coil-winding operation in a manner to be described later. It is also to be understood that in the dot-and-dash position of blades 156 in Fig. 9 there is sufficient clearance between blade tooth 170 and the corner 172 to permit the dot-and-dashed anchor in Fig. 5 to slide deeper into slot 152 and underneath blade tooth 170. Consequently, before the winding head has completed the first revolution of its just completed coil-winding operation, the anchored supply wire which is kept under slight tension by any suitable tensioning means (not shown) causes the anchor to slide underneath blade tooth 170, i. e. out of the operating region of the anchor bending edge 166 of blade 156b. It can now be understood that when the end of the just-wound coil is guided into the shallow groove 150, the anchored start lead of said coil is in cooperative alignment with the cooperating shearing edges 168 and 178 of blade 156b and plate 154, respectively. Therefore, the machine being stopped after the winding of a coil, the blades 156 are again moved into the full line position shown in Figs. 5 and 9, thereby severing the trailing end of the wound coil from the supply wire due to cooperation of the shearing edges 162 and 164 of blade 156a and plate 154, respectively, anchoring the severed end of the supply wire to the winding head A by the bending edge 166 of blade 156b and severing the start lead of the wound coil from its anchor in slot 40 152 underneath blade tooth 170 due to cooperation between the shearing edge 168 and 178 of blade 156b and the adjacent plate 154, respectively. Groove 150, where it traverses slot 152, is of such depth that when the anchored end 45 of the coil lead is in engagement with the groove bottom 180, the anchor is in operative alignment with the cooperative shearing edges 168 and 178 as can be best seen from Fig. 9. Upon a restart of the machine, the anchored 50 supply wire is again immediately guided into the winding groove 56 by the shallow groove 150 and the anchor is forced underneath blade tooth 170 into operative alignment with the shearing edges 168 and 178 so as to clear that part of groove 150 which is above blade tooth 170 for the subsequent reception of the trailing end of the coil being wound. The dot-and-dash line in Fig. 6 represents diagrammatically a wound coil with its starting and trailing leads in that 55 position relative to the blades 156 which they assume at the end of the winding operation and prior to the operation of said blades.

The loop 182 represents the sides, 184 represents the anchored start lead and 186 represents the trailing end, of the wound coil and also the starting end of the supply wire to be subsequently anchored to the winding head A for the next winding operation.

It has been already explained that at the completion of a winding operation the winding head assumes a position in which the blades 156 are in alignment with the plunger 176, adapted to rock these blades from the dot-and-dash position in Fig. 9 to the full line position thereof. As best shown in Fig. 13, this plunger

176 is in the form of a pin threaded into a cam follower 190, being provided with an anti-friction roller 192 which is adapted to cooperate with the camming surface 194 of a lever 196 which is pivotally mounted at 198 to a bracket 200 on top of one of the bearings 34. The cam follower 190 is guided for linear movement in a guide 202 and the roller 192 is normally urged into engagement with the camming surface 194 by means of a compression spring 204. The pin or plunger 176 is longitudinally adjustable relative to the follower 190 and may be locked in adjusted position by means of a nut 206. Lever 196 is connected with bar 70 (see Figs. 3a and 12) by means of suitable links 208 and 210, so that depression of the foot pedal 72 not only causes a separation of the winding members 38 and 54 in the earlier explained manner but also a rocking of the lever 196 in clockwise direction as viewed in Fig. 12, whereby the camming surface 194, cooperates with the follower 190 to force plunger 176 to the right as viewed in Figs. 3a and 13, thereby moving the blades 156 from the dot-and-dash position in Fig. 9 to the full line position thereof. A tension spring 211 returns bar 70, links 210, 208 and lever 196 with its camming surface 194 into the position shown in Figs. 3a, 12, and 13, immediately after the operator releases the foot pedal in the depressed position, shown in dot-and-dash lines in Fig. 3a. It is obvious that pin 176 is thereafter immediately forced into the retracted position shown in Figs. 3a and 13 under the compression of spring 204. It is essential that after resumption of operation of the machine, the blades 156 are withdrawn from the full line position into the dot-and-dash position shown in Fig. 9, before the winding head A completes one revolution, so as to permit the anchor on the supply wire to be drawn underneath blade tooth 170 in the earlier explained manner before the tension in the wire becomes ineffective on said anchor by several wire depositions in the winding groove 56. To accomplish this end, a cam 212 is mounted on the machine base 38 as best shown in Fig. 11. Adapted to cooperate with this cam 212 during the first revolution of the winding head in each winding operation are the laterally projecting ends 214 of the blades 156 when in the full line or operative position of Figs. 5 and 9. The surfaces 216 of said blades are then engaged by said cam and are rocked thereby into the retracted, inoperative position shown in dot and dash lines in Fig. 9. The winding head A revolves substantially through three-quarters of a revolution when the blades 156 finally assume the dot-and-dash position in Fig. 9, and the anchor on the supply wire is then immediately drawn underneath blade tooth 170 under the tension of the supply wire which is still effective on said anchor since less than one complete layer of wire has been deposited in the winding groove 56.

Machine stopping and restarting device D

Referring more particularly to Figs. 2, 3, 12, 14, and 15, the control shaft 102 carries a cam 220 which is adapted to cooperate with a rocker arm 222, pivotally mounted at 224 to the machine base 38 and projecting into an annular groove 226 in the hub 228 of the slidable friction disc 42. A suitably mounted torsion spring 230 normally rocks arm 222 into engagement with cam 220. The ratio in speed between the form driving shaft 36 and control shaft 102 is such that the latter

is indexed one complete revolution during a complete coil winding operation. Therefore, cam 220 is so angularly adjusted on shaft 102 that immediately before the conclusion of a winding operation, the cam lobe 232 rocks arm 222 sufficiently clockwise as viewed in Fig. 2 as to withdraw disc 42 from frictional driving engagement with pulley 44. However the rapidly revolving winding head does not immediately come to rest after such disengagement of the clutch, and it is obvious that shaft 102 likewise does not immediately come to rest but is further indexed in spite of the provision of the friction brake 234 which embraces the periphery of cam 220 and is tensioned by means of a screw 236, threaded into a post 238 on the machine base 30 (see Fig. 12). However, to prevent a self-executed restart of the machine due to free rotation of the winding head A and control shaft 102 until the cam lobe 232 has cleared arm 222, rotation of the winding head A is positively stopped while the cam lobe 232 still holds arm 222 in clutch disengaging position. This is accomplished by providing the hub 228 of friction disc 42 with a notch 240 which is adapted to be engaged after clutch disengagement by a stop 242 which is pivotally mounted at 244 to a block 246, bearing against a shock absorber 248 of soft rubber or other suitable material. Blocks 250 and a cover plate 252 retain the bearing block 246 in proper position. More particularly stop 242 is fast on the pivot 244 which has a depending arm 254 terminating in a cam follower 256, adapted to cooperate with a cam 258 on control shaft 102. A tension spring 260 normally retains follower 256 in engagement with cam 258 and the stop 242 withdrawn from the notch 240. Cam 258 is so angularly relative to cam 220 that the lobe 262 of cam 258 rocks the stop 242 against the face 264 of hub 228 shortly before the notch 240 registers with said stop 242. It can now be understood that immediately after the friction disc 42 is moved slightly against the compression of spring 48 out of driving engagement with pulley 44, stop 242 is forced against the hub face 264 until the notch 240 is in registry with said stop, whereupon the latter enters said notch and stops the freely rotating clutch disc 42 together with the winding head A and control shaft 102. This sudden stopping of the clutch disc 42 naturally results in a shock being transmitted to the stop 242, which shock is taken up by the rubber cushion 248 as can be readily understood. By the time the winding head comes to a forced rest, the cams 258, 220 assume the position shown in Fig. 15, in which their lobes 262 and 232, respectively, are in operative engagement with the follower 256 and arm 222, respectively. It will be noticed from Fig. 15 that upon renewed rotation of control shaft 102 in the direction of arrow 268 in Fig. 15, the follower 256 will clear cam lobe 262 sooner than rocker arm 222 will clear cam lobe 232, wherefore the stop 242 is withdrawn from locking engagement with the notched hub 228 before the rocker arm 222 permits reengagement of the friction disc 43 with the pulley 44. It is obvious that the lateral shifting of the wire into the winding groove 56 for a complete coil has to take place during one complete revolution of control shaft 102. The wire shifter actuating cam 134 therefore has to be designed accordingly.

It is now well understood that the machine is stopped at the conclusion of a winding operation and that the operator thereafter depresses the foot pedal 72 in order to cause a separation of

the winding members 38, 54 and to actuate the wire severing and anchoring blades 156. However, after the machine has come to rest and before the operator depresses foot pedal 72, he grasps one of the coil sides 100a in the winding groove 56 by means of any suitable clamp which he introduces into said winding groove through suitable notches 270 in the winding members 38, 54. The operator then depresses foot pedal 72, and by the time winding member 54 has receded from its companion member 38 sufficiently far to permit the lateral removal of the coil, the severing and anchoring blades 156 have performed their operation and released the coil from the winding form. As already explained, release by the operator of the foot pedal 72 from depressed position causes a reengagement of the winding members 38, 54 and a withdrawal of the blade-actuating plunger 176 into the full line position shown in Fig. 3a. Such withdrawal of plunger 176 is accompanied by movement of the links 208, 210 in the direction of arrow 272 into the position shown in Fig. 12. Such movement of the links 208 is utilized for restarting the machine in a manner to be explained presently. Adjustably secured to the control shaft 102 in any suitable manner is a finger 274 which assumes the angular position shown in Fig. 12 during rest periods of the machine. Pivotally mounted at 276 to the two parallel links 208 (see Figs. 12 and 15) is a lever 278 which is normally urged into the position shown in Fig. 14 by means of a suitably mounted torsion spring 280. In this position, lateral lugs 292 of lever 278 bear against the parallel links 208 and thus prevent clockwise rotation of said lever beyond the position in Fig. 14. During movement of the links 208 in the direction of arrow 272 in Fig. 12 upon release of the foot pedal by the operator, lever 278, which then assumes the normal position shown in Fig. 14, engages finger 274 in the position shown in Fig. 12 and rocks the same and the control shaft 102 into the position shown in Fig. 14. During such rocking of the control shaft 102 as caused by the lever 278, the cam lobes 262 and 232 of the cams 258 and 220, respectively, clear the follower 256 and arm 222, thus restarting the machine by permitting clutch reengagement in the earlier explained manner. During the latter part of a winding operation, the finger 274 reapproaches the lever 278 and rocks the same counterclockwise until it finally assumes the position in Fig. 12 at the end of the winding operation. During the following depression of the foot pedal by the operator, the lever 278 is yieldingly returned into the position shown in Fig. 14 immediately after it clears the finger 274 in the position shown in Fig. 12, thus resetting the lever 278 for a restart of the machine after release of the foot pedal by the operator.

In order to prevent serious damage to certain machine elements by an accidental tripping of the foot pedal 72 by the operator or in any other way while a winding operation is in progress, the foot pedal 72 is positively locked against depression while the machine is in operation. To this end link 74, which connects the foot pedal 72 with bar 78 is provided with an adjustable lug 293 which has a notch 292. Adapted to be received in said notch 292 is one arm 294 of the earlier mentioned bell crank lever 142. This arm 294 is provided with a shoulder 295 which is adapted to bear against the lower surface 293 of lug 293 while the machine is in operation, thus effectively preventing a tripping of the foot pedal 75.

72 as can be readily understood. Of course shoulder 296 is long enough to remain in engagement with shoulder 298 in spite of the nominal oscillations of the wire shifter B during winding, 5 which oscillations are transmitted to the bell crank lever 142 by rod 146 which is in constant yielding engagement with the wire shifter. However, shortly before a winding operation is completed, the wire shifter is swung into the dot-and-dash position, shown in Fig. 10, in order to guide the trailing end of a just wound coil into the groove 150, and this deviation of the wire shifter from its normal region of oscillation is sufficient to cause a rocking of lever 142 into the 10 dot-and-dash position of Fig. 3a, in which the shoulder 236 has no restraining influence on the pedal 72 any more. Of course, immediately after the machine is restarted cam 134 returns the wire shifter to its normal region of oscillation, 15 thereby also permitting lever 142 to return into the pedal restraining position, as can be readily understood.

While the embodiment of the present invention as herein disclosed, constitutes a preferred form, 25 it is to be understood that other forms might be adopted, all coming within the scope of the claims which follow.

I claim:

1. In a winding machine having a separable 30 winding form and a wire shifter, the combination of means for causing relative linear movement between form and shifter; a manually operable device for separating the form; and mechanism locking the device against manipulation while 35 the shifter and form are within a pre-assigned region of said relative movement.

2. In a winding machine having a separable 40 winding form and a linearly movable wire shifter, the combination of manually operable means for separating the form; and mechanism locking said means against manipulation while the shifter is within a pre-assigned region of its movement relative to the form.

3. In a winding machine having a winding form 45 and a wire shifter, the combination of means for severing the wire between form and shifter; means for causing relative linear movement between form and shifter; a manually operable device for actuating the severing means; and mechanism locking the device against manipulation while the form and shifter are within a pre-assigned region of said relative movement.

4. In a winding machine having a winding form 50 and a linearly movable wire shifter, the combination of means for severing the wire between form and shifter; a manually operable device for actuating the severing means; and mechanism locking the device against manipulation while the shifter is within a pre-assigned region of its 55 movement relative to the form.

5. In a winding machine having a winding form 60 and a linearly movable wire shifter, the combination of means for severing the wire between form and shifter; a manually operable device for actuating the severing means; and mechanism locking the device against manipulation while the shifter is within a pre-assigned region of its 65 movement relative to the form.

6. In a winding machine having a separable 70 winding form and a wire shifter, the combination of means for severing the wire between form and shifter; means for causing relative linear movement between form and shifter; a manually operable device for actuating the severing means 75 and separating the form; and mechanism locking

the device against manipulation while the form and shifter are within a preassigned region of said relative movement.

7. In a winding machine having a separable 5 winding form and a linearly movable wire shifter, the combination of means for severing the wire between form and shifter; a manually operable device for separating the form and actuating the severing means; and mechanism locking the device against manipulation while the shifter is within a pre-assigned region of its movement relative to the form.

8. In a winding machine having a separable 10 winding form and a linearly movable wire shifter, the combination of means for severing the wire between form and shifter; a manually operable device for separating the form and actuating the severing means; and mechanism locking the device against manipulation while the shifter is within a pre-assigned region of its movement 15 relative to the form, and releasing the device for manipulation when the shifter moves beyond said pre-assigned region.

9. In a winding machine having a winding 20 form and a wire shifter, the combination of power 25 means for causing relative rotation between form and shifter; means for causing relative linear movement between form and shifter; a controller rendering the power means ineffective upon a completed winding operation; a manually operable 30 device for rendering the power means effective; and mechanism locking the device against manipulation while the form and shifter are within a pre-assigned region of said relative linear movement. 35

10. In a winding machine having a rotatable 40 winding form and a linearly movable wire shifter, the combination of power means for rotating the form; a controller rendering the power means ineffective upon a completed winding operation; 45 a manually operable device for rendering the power means effective; and mechanism locking the device against manipulation while the shifter is within a pre-assigned region of its movement relative to the form. 45

11. In a winding machine having a separable 50 winding form and a wire shifter, the combination of power means for causing relative rotation between form and shifter; means for causing relative linear movement between form and shifter; a controller rendering the power means ineffective upon a completed winding operation; 55 a manually operable device for separating the form and for rendering the power means effective; and mechanism locking the device against manipulation while the form and shifter are within a pre-assigned region of said relative linear movement.

12. In a winding machine having a winding 60 form and a wire shifter, the combination of means for severing the wire between form and shifter; power means for causing relative rotation between form and shifter; means for causing relative linear movement between form and shifter; a controller rendering the power means ineffective upon a completed winding operation; 65 a manually operable device for actuating the severing means and for rendering the power means effective; and mechanism locking the device against manipulation while the form and shifter 70 are within a pre-assigned region of said relative linear movement.

13. In a winding machine having a separable 75 winding form and a wire shifter, the combination of means for severing the wire between form

and shifter; power means for causing relative rotation between form and shifter; means for causing relative linear movement between form and shifter; a controller rendering the power means ineffective upon a completed winding operation; a manually operable device for separating the form and actuating the severing means and rendering the power means effective; and mechanism locking the device against manipulation 10 while the form and shifter are within a pre-assigned region of said relative linear movement.

14. In a winding machine having a separable winding form and a pivotally mounted wire shifter, the combination of a rotatable cam having 15 portion for rocking the shifter within a pre-assigned region for winding and a portion for rocking the shifter beyond said region; a manually operable device for separating the form; and mechanism actuated by the shifter for locking 20 the device against manipulation while the shifter is within said region, and for releasing the device for manipulation when the shifter moves beyond said region.

15. In a winding machine having a separable 25 winding form and a pivotally mounted wire shifter, the combination of a rotatable cam having portion for rocking the shifter within a pre-assigned region for winding and a portion for rocking the shifter beyond said region; means including a foot pedal for separating the form, said pedal having shoulder; and a pivotally mounted lever having a shoulder and being rocked by the shifter such that the lever shoulder engages the 30 pedal shoulder and prevents manipulation of the pedal while the shifter is within said region, but withdraws from the pedal shoulder when the shifter moves beyond said region.

16. In a winding machine having a winding

form, the combination of power means; a normally engaged clutch drivingly connecting the power means with the form; rotary means adapted at the end of a complete revolution to disengage the clutch, said means being rotated by the 5 form at reduced speed and having a depending finger; and mechanism including a foot pedal and a pivotally mounted pawl yieldingly retained in a normal position and movable with the pedal and being deflected from normal position by the 10 passing finger during the latter part of one revolution of the rotary means, said pawl clearing the finger and returning to normal position upon depression of the pedal and rocking the finger upon return of the pedal from depressed position, 15 thereby reengaging the clutch.

17. In a winding machine having a winding form, the combination of means for severing a wound article on the form from the winding material; a normally engaged clutch drivingly connecting the power means with the form; rotary means adapted at the end of a complete revolution to disengage the clutch, said means being rotated by the 20 form at reduced speed and having a depending finger; and mechanism including a 25 foot pedal and a pivotally mounted pawl yieldingly retained in a normal position and movable with the pedal and being deflected from normal position by the passing finger during the latter part of one revolution of the rotary means, depression of the pedal causing the mechanism to 30 actuate the severing means, and the pawl to clear the finger and return to normal position, and return of the pedal from depressed position causing the pawl to rock the finger thereby reengaging 35 the clutch.

EDWARD W. COLLINS.
